APPARATUS FOR TREATMENT OF STAPLE FIBER

Erwin Bauer, Wuppertal-Elberfeld, and August Lindel and Hans Tegetmeyer, Greben, Germany, assignors to North American Rayon Corporation, New York, N. Y., a corporation of Delaware

Application November 27, 1936, Serial No. 113,024.
In Germany November 29, 1935

3 Claims. (Cl. 18—8)

The present invention relates to the manufacture of yarn of artificial origin, but primarily is concerned with the washing and after-treatment of freshly spun artificial silk cut up into staple fibers.

In the manufacture of staple fibers from artificial silk, a large number of threads extruded through spinnerettes are usually collected into rope-like skeins of very high denier which in this form are cut up into small pieces of thread. The staple fibers thus obtained are then washed, after-treated and dried. These wet treatments were hitherto carried out in large vats, and since up to the present the artificial silk yarn was always cut up into very short pieces, these vats served the purpose very well. However, the industry now demands staple fibers having a length of 10, 12, 15 and more centimeters, so that considerable difficulties have arisen in the employment of the above mentioned vats. Owing to the greater length of the fibers it was found that the material became matted during the wet treating process, resulting in harmful injuries in the fibers.

It is therefore an object of the present invention to devise an apparatus which can be satisfactorily employed for the after-treatment of long sized staple fibers.

Another object of the present invention lies in the fact that with the new apparatus the staple fiber can be after-treated in a continuous operation.

These and other objects will in part become obvious and will in part be pointed out in the following specification and appended claims when taken in conjunction with the attached drawings.

In accordance with the present invention the staple fibers are spread out and uniformly distributed into a continuous band-like fleece. The latter is then deposited upon an endless perforated conveyor belt. The different after-treating baths, such as desulphurization bath, bleaching bath, reviving bath, and the like are sprayed upon the staple fibers by means of numerous nozzles as they are transported by the conveyor belt. A number of conveyor belts are usually arranged in series so that the various after treatments can be carried out individually. Press rollers through which the fleece passes are positioned between adjacent conveyor belts, and are employed to remove from the fibers excessive treating liquid used in the preceding bath.

The conveyor belts are sloped in the direction of travel of the fleece, thus providing space for the positioning of the press rollers between ad-

jacent conveyor belts, while on the other hand the treating liquid is allowed to flow backwardly on the slanting surface of the conveyor belts. The liquid pressed from the staple fiber fleece 5 may be collected in troughs arranged below the press rollers. In order to facilitate the flow off of the liquid from the press rollers, the lower roller may be provided with an inclined, endless rubber belt passing around a third roller and forming an imperforate slanting surface on which the liquid may flow back into the collecting means.

The different parts of the machine should be constructed from material which cannot be corroded by the chemicals used for the various treating baths. It was found that acid-proof steel wire gauze may be best used as conveyor belts. The press rollers may be made of iron covered with rubber, while the frame of the machine may be protected against chemicals by means of lead lining, rubber coating and the like.

The spraying system may consist of a series of pipe lines provided with fine spraying holes 25 and is positioned a short distance above and/or below the conveyor belts carrying the staple fiber fleece, or any other suitable device may be used for spraying liquid in a finely divided form upon the fleece. Troughs for the collection of the used liquid are arranged below the conveyor belts. These troughs may be provided with pipe lines and pumps in order that the waste liquid 30 may be used again for after-treating purposes.

It is of importance that the freshly cut up 35 staple fibers which still contain chemicals from the precipitating bath are subjected to the after-treating process in the form of a uniformly distributed fleece while being transported by the conveyor belts. In order to prepare the staple fibers 40 accordingly, they are first passed through a chute-like chamber in which water or any other liquid is sprayed from numerous holes upon the fibers from above and below while the fibers automatically advance along a surface sloped 45 in the direction of travel of the fibers. Because the liquid is forced upon the staple fibers under pressure, the freshly cut staple fibers are dispersed and a uniform fleece is formed. The chamber in which this treatment takes place is 50 of chute-like shape, and since the side walls of this chamber can be changed with respect to their distance from each other, it is possible to vary the width and consequently the thickness of the staple fiber fleece. The possibility of varying the width and thickness of the fleece is very

important because it was found that some after-treating processes are more efficiently carried out on a thin fiber fleece and others on a thick fiber fleece.

Similar treating chambers may also be arranged between adjacent conveyor belts, i. e., between different after-treating baths, in order to improve the efficiency of the various baths because of the possibility of varying the width or thickness of the fiber fleece.

In the drawings in which

Fig. 1 is a diagrammatic longitudinal cross section of the new machine, and

Fig. 2 is a detailed vertical section of the special treating chamber.

Like numerals of reference refer to like parts. 1 indicates the perforated conveyor belt which is loaded with freshly cut staple fibers 7 and which feeds them to the chute-like treating and preliminary washing chamber 2 shown in Fig. 2. They enter the latter at the upper end 3 and after being sprayed with liquid from above and below emerge in the form of a well distributed fleece through the outlet 4. The fiber fleece is now fed to the first conveyor belt 5 which transports it parallel with and below the spraying devices 6, 6a, and 6b. At the end of the first conveyor belt the fleece 7 is passed through two press rollers 8 and 9 in order to extract excessive liquid therefrom which was used in the first bath. Most of the liquid so extracted flows into the receiving device 10. The fiber fleece is now led to the second conveyor belt and is treated by means of the spraying devices 12, 12a, 12b. At the end of the second conveyor belt 11 an expressing device is arranged which makes it possible to carefully separate the liquid extracted by the rollers from that used in the subsequent bath. The two press rollers 13 and 14 are therefore arranged in a more vertical position and the lower roller 14 is joined to a third roller 25 by means of an endless rubber belt 15. The latter is provided to lead the liquid into the receiving device 16. The fiber fleece is then passed to the third conveyor belt 17 in order to be subjected to further after-treatments. Suitable troughs 18, 18a, 18b, 19 and 19a are positioned below the different conveyor belts for the collection of liquid dripping from the latter. These troughs may either comprise one trough for each conveyor belt as in 20, or they may be divided into individual troughs for each spraying device.

As shown in Fig. 1, spraying devices 26, 26a, and 26b similar in all respects to those designated 6, 6a, and 6b may be disposed in corresponding positions below the upper run of the perforated first conveyor belt 5.

Fig. 2 shows the device in which the freshly cut staple fibers are formed into a uniformly distributed fleece. By means of the pipe lines 21 and 22 treating liquid is forced through the nozzles 23 and 24. The latter are so arranged that the nozzles of one side are not in line with those of the other side, thus it is assured that the staple fibers are sprayed uniformly from all sides.

The open-ended treating chamber 2 is tapered 10 from above to below, and the width of the lower outlet 4 can be changed by means of shifting the side walls of the treating chamber. It also appears advisable to position the nozzles in a direction whereby the liquid will advance the 15 staple fibers forwardly as the fleece is built up.

Having now described the invention as required by the patent statutes, what is claimed is:

1. In an apparatus for use in the after-treatment of staple fiber, a forming chute adapted 20 to receive staple fibers, means to vary the width of the outlet end of said chute, and means to uniformly distribute the staple fibers in said chute, said distributing means comprising a plurality of nozzles arranged on opposite faces of the chute 25 and in staggered relationship to each other and adapted to spray liquid under pressure simultaneously from below and above against the staple fibers to uniformly distribute them into a fleece.

2. In an apparatus for the after-treatment of 30 staple fiber, a washing and feeding device comprising an open-ended chamber which is in the form of a tapered chute sloped downwardly with respect to the general direction of travel of the staple fiber, and a plurality of pressure spray 35 means located inside the chamber at the top and bottom thereof and arranged to form the fibers into a uniformly distributed fleece and to advance them as the fleece is built up.

3. In an apparatus for the after-treatment of 40 staple fiber, the combination with a pair of conveyor belts arranged in series with the first belt spaced above the succeeding belt at their adjacent ends, of a washing and feeding device connecting said adjacent ends of the conveyor belts, 45 said washing and feeding device including an open-ended chute chamber tapered toward its outlet end and a plurality of pressure means inside said chamber at the top and bottom thereof arranged to form the fibers into a uniformly distributed fleece and to advance them as the 50 fleece is built up.
